UNITED STATES PATENT OFFICE

HERMAN MAYER, OF PHILADELPHIA, PENNSYLVANIA

APPARATUS FOR SOFTENING SILK, YARN, COTTON, AND OTHER THREAD

Application filed May 3, 1928. Serial No. 274,779.

This invention relates to apparatus for softening silk, yarn, cotton, or other thread, and relates more especially to a device for moistening silk, yarn, cotton or other thread as it passes from a bobbin or cone to a knitting or weaving machine.

The leading object of the present invention is to provide a device of the character stated in which a receptacle for yarn moistening purposes is provided arranged to contain a liquid and having suspended from the upper part of the receptacle a wick doubled over upon itself with its pendant lower ends submerged in the liquid, said wick being so suspended that the thread is guided horizontally between and in contact with the pendant ends of the wick.

A further object of the present invention is to provide a device of the character above stated in which the wick is suspended from a rod arranged substantially horizontally of the receptacle and in which thread is guided through said receptacle including the pendant ends of said wick in substantial parallelism with said rod.

A still further object of the present invention is to provide a closed chamber arranged within the liquid containing receptacle, which closed chamber has a heating medium therein for raising the temperature of the liquid in the receptacle, which heating medium is isolated from the liquid chamber.

Other and further objects of the present invention reside in the provision of general details of construction and arrangement and combination of parts for attaining the results sought by the foregoing objects.

Other and further objects not at this time set forth will hereinafter appear.

The nature, characteristic features and scope of the invention will be more fully understood from the following description taken in connection with the accompanying drawings forming part hereof, and in which:

Fig. 1, is a top or plan view of apparatus for softening silk, yarn, cotton, and other thread embodying the invention.

Fig. 2, is a view in horizontal section taken upon the line 2—2 of Fig. 1.

Fig. 3, is a view in cross section taken upon the line 3—3 of Fig. 1.

Fig. 4, is a view in cross section taken upon the line 4—4 of Fig. 1.

Fig. 5, is a top or plan view of apparatus for softening silk, yarn, cotton and other thread embodying a modified feature of the invention.

Fig. 6, is a view in longitudinal section taken upon the line 6—6 of Fig. 5.

Fig. 7, is a view in perspective illustrating details of construction shown in Fig. 6.

For the purpose of illustrating my invention I have shown in the accompanying drawings two forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Broadly stated, the apparatus for softening silk, yarn, cotton, and other thread embodied in the present invention comprises a receptacle of generally rectangular form adapted to have passed therethrough thread as it leaves a bobbin or cone for delivery to a knitting or weaving machine, said thread passing between a doubled over wick, which wick has its pendant lower ends submerged in liquid within the receptacle and in which the thread is guided substantially in parallelism with the means for supporting the wick, and in which a closed chamber is arranged within a liquid containing receptacle so that the heating medium therein is isolated from the liquid chamber.

Referring now to the drawings in detail, 1 designates a receptacle which may be of any desired configuration, but which in practice is of rectangular shape. This receptacle is calculated to contain water or other liquid, 95 and the open top is provided with a removable cover 2. Carried by the side walls 3 of the receptacle and extended horizontally through the receptacle 1 immediately below the cover 2 is a plurality of rods 4, the num- 100

ber of which is immaterial, five being shown in the drawings. Suspended upon each rod 4 is a wick 5 doubled over upon itself so as to provide pendant lower ends 6 the pendant ends being spaced apart, as clearly shown in Fig. 4. The lower pendant ends of the wick 5 are submerged in the liquid contained in the receptacle 1 so that the wicks at all times absorb liquid contained within the receptacle. Arranged within the side walls 3 adjacent the wicks 5 and immediately below the rods 4, and in alignment with said rods, is a plurality of inlet eyelets 7 for guiding thread to and between the pendant parts of the wicks and to the elongated exit opening 9, see Fig. 2.

Arranged beyond the wicks 5 and carried by the bottom wall of receptacle 1 is a casing 10 enclosing a chamber 15, the major portion 20 of which casing in practice is formed integral with receptacle 1, see Fig. 2, a cover 11 located wholly without the receptacle 1 being provided for gaining access to the chamber 15. While the chamber 15 may be 25 provided with any appropriate heating medium, for illustrative purposes electric heating coils 12 are provided which coils are mounted upon a block of insulating material 13, and secured to the casing 10 of chamber 30 15 as by screws 14. Electrical connection is made with the coils 12 through wires 16 and 17. These wires 16 and 17 pass through pipes 18. A liquid inlet connection 19 is provided and a liquid outlet 20 is also provided, as clearly shown in Figs. 1 and 4. The number 35 of units installed upon an apparatus may be of any desired number, as, for instance, from one to thirty or more units. They are so arranged with the piping connections that the units are all connected in series by pipe 40 lines 19 and 20 or liquid may be supplied by separate and independent containers per unit.

The receptacle 1 can be made of any suitable material as cast iron, white metal, brass, copper, porcelain, or glass. The heating unit in the oven or chamber 15 is easily accessible and likewise its connections in the wiring chamber.

My novel softener can be attached to a full fashioned hosiery machine, a circular knitting machine, or to silk spinning, weaving and winding machines, as is evident.

The electric heating element has an important function, since it not only heats the water, felt and the threads which are to be softened, but it also has a tendency as the temperature increases to generate a vapor which softens and lubricates the thread and the resultant fabric into which the thread is knitted.

The heating coils arranged within the closed chamber 15 provide a heating medium which is isolated from the liquid chamber 65 so that no heat escapes from the chamber, but

rather the coils 12 heat the casing 10 which in turn raises the temperature of the liquid within receptacle 1. Thus, no actual heat directly impinges against the thread passing through the receptacle unduly to heat and 70 dry out the thread.

The receptacle 1 can be filled to the desired height with water or any other liquids with the felt wicks 5 partly submerged. These wicks will at all times absorb the various liquids and will always be saturated. As the threads pass through and contact with the juxtaposed walls of said felt wicks they will absorb the water or liquids used, and in so doing will be readily lubricated, softened and moistened, making the threads so flexible, that the life of the needles and guides which otherwise are liable to break or become fractured by the hardness of the threads, will be indefinitely prolonged.

The use of my novel device further eliminates the use of some winding machinery, as today many of the threads or yarns can be purchased on cones and can be used as purchased directly on the knitting machine. 90 In many cases at the present time, however, silk and like threads are wound and rewound many times in order to take the hardness and stiffness out of them. My novel device dispenses with this procedure, since it lubricates 95 and softens the threads and the resultant fabric and thereby saves an extra operation of re-winding the thread in order to apply some sort of a lubricant thereto.

Referring now to the modified form shown 100 in Figs. 5 to 7 inclusive, the general arrangement, construction, and combination of parts is the same as that shown in the foregoing figures with the exception that instead of the electric heating apparatus shown in the chamber 15 in Figs. 2 and 3, the said electric heating apparatus has been omitted and a chamber provided for steam or hot water heating. This chamber is designated 15', and is not integral with the casing 1. The chamber 15' is enclosed by casing 21, the lower stem 22 of which is internally screw threaded to accept a nipple or short section of pipe 23. The nipple 23 extends through the bottom of the casing 1 and has screw 110 threaded arrangement with casing 21, a nut 24 being provided for clamping the casing 21 with respect to casing 1. Washers or packing 25 of appropriate material are interposed between the meeting faces of the stem 22 of casing 21 and the inner face of nut 24. When these parts are firmly clamped to place, as shown in Fig. 6, the chamber 15' is isolated from the contents of the receptacle 1, as is clearly apparent from Fig. 6 of the drawing.

While I have shown the casing 21 as being of rectangular form, it is obvious that any other shape if desired may be employed, and the manner of packing the nipple 22 and of 130

making a tight joint between the stem of the heating chamber and the bottom wall of the receptacle can be varied if desired. When the construction seen in Fig. 6 is employed, it 5 will be understood that the bottom wall of the receptacle is solid except for the opening 26 therein through which the nipple 23 passes.

I am aware that the invention may be embodied in other specific forms without departing from the spirit or essential attributes thereof, and I therefore desire the present embodiment to be considered in all respects as illustrative and not restrictive, reference 10 being had to the appended claims rather than to the foregoing description to indicate the scope of the invention.

Having thus described my invention, what I claim as new, and desire to secure by Letters 15 Patent, is:

1. In a device of the character stated, a receptacle for thread moistening purposes adapted to contain a liquid, a rod extended longitudinally of said receptacle in the upper 25 part thereof, a wick doubled over upon itself and supported by said rod, said wick having its pendant lower ends submerged in said liquid, thread guiding means arranged below the top of said wick substantially in 30 parallelism with said rod for guiding said thread between and in contact with the pendant portions of said wick, a closed chamber arranged within the liquid containing receptacle, and a heating medium for said chamber, said heating medium being isolated from 35 the liquid in said receptacle.

2. In a device of the character stated, a receptacle for thread moistening purposes adapted to contain a liquid, a rod extending 40 longitudinally of said receptacle in the upper part thereof and supported by the receptacle end walls, a wick doubled over upon itself and supported by said rod, said wick having its pendant lower ends submerged in said 45 liquid, thread guiding means arranged below the top of said wick including inlet eyelets carried by the end walls of said receptacle and arranged substantially in parallelism with said rod for guiding the thread to be moistened between and in contact with the pendant portions of said wick, a closed chamber arranged within the liquid containing receptacle, and a heating medium for said chamber, said heating medium being isolated from 50 the liquid chamber.

3. In a device of the character stated, a receptacle for thread moistening purposes adapted to contain a liquid, a rod positioned in the upper part of said receptacle, a wick 60 doubled over upon itself and supported by said rod, said wick having its pendant lower ends submerged in said liquid, thread guiding means arranged below the top of said wick substantially in parallelism with said rod 65 for guiding the thread between and in con-

tact with the pendant portions of said wick, a detachable heating chamber in said receptacle and isolated from the liquid therein, a removable cover for the top of said receptacle, said wicks being positioned in the space between said heating chamber and an end wall 70 of said receptacle, and means for securing said heating chamber to a wall of said receptacle.

4. In a device of the character stated, a receptacle for thread moistening purposes adapted to contain a liquid, wick supporting means in the upper part thereof, a wick doubled over upon itself and positioned on said supporting means, said wick having its 75 pendant lower ends submerged in said liquid, thread guiding means arranged below the top of said wick substantially in parallelism with said wick for guiding the thread between and in contact with the pendant portions 80 thereof, a closed detachable heating chamber isolated from the liquid in said receptacle, said wick being positioned in the space between said heating chamber and an end wall 85 of said receptacle, a lower internally threaded stem on said heating chamber, supported on a wall of said receptacle, a nipple engaging said stem and projecting through said receptacle wall, packing surrounding said nipple within and without said wall, and a 90 nut engaging the outer end of said nipple.
